(57) CLAIM

The ornamental design for bed skirt with pockets, as shown and described.

DESCRIPTION

FIG. 1 is a perspective view of a bed skirt with pockets, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention; and,

FIG. 6 is a top plan view of the invention.

The broken lines showing a box spring and frame in FIG. 3 are included for the purpose of illustrating the invention in use, and form no part of the claimed design. The bottom plan view is not visible during normal use and forms no part of the claimed design.
